148,977

DESIGN FOR A CAMERA

Jack Briskin and Joseph J. Golick, Chicago, Ill.
assignors to Revere Camera Company, Chicago,
Ill., a corporation of Delaware

Application November 7, 1947, Serial No. 142,376

Term of patent 14 years

(Cl. D61—1)

To all whom it may concern:

Be it known that we, Jack Briskin and Joseph J. Golick, respectively, citizens of the United States, residing at Chicago, in the county of Cook and State of Illinois, have invented a new, original, and ornamental Design for a Camera, of which the following is a specification, reference being had to the accompanying drawings, forming a part thereof, in which,

Fig. 1 is a perspective view of a camera showing our new design;

Fig. 2 is a front view thereof;

Fig. 3 is a bottom view thereof;

Fig. 4 is a view of the side thereof opposite the side shown in perspective in Fig. 1;

Fig. 5 is a rear view thereof; and
Fig. 6 is a top view thereof.

We claim:

The ornamental design for a camera, as shown.

JACK BRISKIN.

JOSEPH J. GOLICK.
